UNITED STATES PATENT OFFICE.

HENRIETTA F. DUKE, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 18,284, dated May 1, 1888.

Application filed April 2, 1888. Serial No. 264,381. Term of patent 3½ years.

To all whom it may concern:

Be it known that I, HENRIETTA F. DUKE, of the city, county, and State of New York, have invented and produced a new and original Design for a Pattern of a Lady's Costume; and I do hereby declare that the engraved prints accompanying this specification convey to any one accustomed to using paper patterns a clear understanding of how a garment made up by the pattern will appear.

The design shows a basque and a round walking-skirt. The skirt displays a long front drapery in two parts, which exhibit draping plaits where they meet and also in their upper and back edges, and a revers turning backward down the left side of the front, a full back drapery falling even with the edge and displaying loopings near the top. The basque displays close-fitting fronts that lap diagonally

below the waist-line and exhibit a curved lapel 20 extending from the left shoulder to below the bust and a longer lapel extending from the right shoulder and along the overlapping edge; a close-fitting back that exhibits its middle seam open for some distance from the bottom 25 and the lower back corners rounded off; a standing collar displaying its front corners reversed, and coat-sleeves.

What I claim as my invention, and desire to secure by Letters Patent, is—

The design for a lady's costume, as shown in the engraved prints accompanying this specification.

HENRIETTA F. DUKE.
